DESIGN FOR A COMBINED BERRY BOWL, PITCHER, AND SUGAR BOWL

Oliver S. Middleton, London, England, assignor to Alice H. Marks, New York, N. Y.

Application October 18, 1940, Serial No. 95,911

Term of patent 7 years

To all whom it may concern:

Be it known that I, Oliver S. Middleton, a subject of the King of Great Britain and a resident of London, England, have invented a new, original, and ornamental Design for a Combined Berry Bowl, Pitcher, and Sugar Bowl, of which the following is a specification, reference being had to the accompanying drawing, forming part thereof, in which:

berry bowl, pitcher and sugar bowl embodying my design;

Figure 2 is a side elevational view thereof; and

I claim:

The ornamental design for a combined berry bowl, pitcher, and sugar bowl, substantially as shown.

OLIVER S. MIDDLETON.
